UNITED STATES PATENT OFFICE.

HARVEY O. NORRIS, OF DAYTON, OHIO, ASSIGNOR, BY MESNE ASSIGNMENTS, TO
GEORGE W. SIMONS, OF DAYTON, OHIO.

PAINT SPRAYER.

Application filed February 25, 1922. Serial No. 539,085.

My invention relates to spraying devices of the air brush type for applying paint, varnish, stain and like material, but also applicable to other purposes, as for instance 5 the spraying of disinfectant, insecticide or in fact, in any use wherein it is desired to distribute a liquid in a form of a fine mist or spray.

The invention contemplates a sprayer head, wherein the liquid is discharged under the influence of compressed air or other fluid under pressure discharged through a suitable jet nozzle in close association to the discharge outlet of the liquid supply conduit whereby the liquid is entrained and discharged in finely sub-divided particles in the manner of an atomizer. The invention further contemplates in such a sprayer device, means for independently controlling 10 the actuating fluid under pressure and the liquid to be discharged, whereby the actuating fluid is initially discharged in advance of the liquid, in order to prime the nozzle to insure uniform discharge and to 15 further remove any dust or foreign matter which may have lodged in the nozzle, prior to the discharge of the paint or other liquid, and further provides for continuing the discharge of the actuating fluid for a short interval of time after the liquid has been arrested in order to thoroughly clear the discharge nozzle of any remaining particles of liquid, thus leaving it empty and clean preparatory for the next period of use.

The object of the invention is to simplify 20 the structure as well as the means and mode of operation of such spraying devices, whereby they will not only be cheapened in construction, but will be more efficient in use, positive in operation, uniform in action, easily controlled and unlikely to get out of 25 repair.

A further object of the invention is to 30 provide an improved form of control valve for both the actuating fluid and the liquid to be discharged, and to further provide for enclosing the actuating springs for such valves.

A further object of the invention is to 35 improve and amplify the construction shown and described in my co-pending application,

Serial No. 478,922, now Patent No. 1,427,495, of which the present application is a continuation in part.

With the above primary and other incidental objects in view as will more fully appear in the specification, the invention consists of the features of construction, the parts and combinations thereof, and the mode of operation or their equivalents as hereinafter described and set forth in the claims.

Referring to the accompanying drawings, wherein is shown the preferred but obviously, not necessarily the only form of embodiment of the invention, Fig. 1 is a side elevation of the assembled sprayer in which is embodied the present invention. Fig. 2 is a longitudinal sectional view of the assembled sprayer head.

Like parts are indicated by similar characters of reference throughout the several views.

While the present sprayer head may be employed in conjunction with a bottle like reservoir or container for paint or other liquid to be sprayed, as is shown in the co-pending application referred to, it is also capable of being connected to a distantly located supply reservoir, from which the liquid is conducted to the sprayer head either under pressure or by gravity. For certain classes of work this supply reservoir, whether of the gravity or pressure type may be of the knapsack style to be carried upon the back of the operator. The particular form of reservoir forming no part of the present invention has not been shown. In lieu thereof, there has been shown in the accompanying drawing, a handle or hand grip portion 1, preferably of tubular form, through which the compressed air and liquid supply conduits may lead, to the sprayer head. This hand grip or handle 1, is provided with a detachable cap or head portion 2, on which the sprayer device or head is mounted.

This spray head comprises a tubular barrel 4, the bore of which is medially contracted or tapered at 5. The angle of this taper is quite acute in relation with the axis of the barrel 4. Screw threaded and hence adjustable upon the forward end of the

barrel 4 is a discharge nozzle 6, having therein a tapered counter bore 7 terminating in a minute discharge orifice 8.

Fixedly located within the barrel 4 and extending within the counter bore of the discharge nozzle 6 is a jet nozzle comprising an elongated hollow stem 9 terminating in a tapered or conical head 10 at one end and having at its opposite end an enlarged 10 tapered or conical head 11, which agrees with the medial tapered contraction 5 of the barrel 4. The enlarged rearward tapered head 11 of the jet nozzle is pressed into firm seating engagement in the tapered 15 socket formed by the contraction 5 of the barrel by a threaded collar 3. The elongated hollow stem 9 of the jet nozzle is thus supported in concentric spaced relation with the walls of the barrel 4 and the counter 20 bore of the discharge nozzle 6. The tapered forward extremity 10 of the jet nozzle extends within the tapered portion of the counter-bore of the discharge nozzle 8 wherein its relation is varied by the adjustment 25 of the discharge nozzle. Thus by a rotary adjustment of the discharge nozzle 6, the outlet orifice 8 thereof may be brought more or less closely into proximity to the tapered head of the jet nozzle and the relation 30 of the tapered extremity of the jet nozzle with the tapered wall of the counter-bore of such discharge nozzle correspondingly varies. The concentric spaced relation of the jet nozzle stem 9 within the bore of 35 the barrel 4 affords thereabout a concentric passage 12 which communicates with the outlet orifice 8.

Extending downwardly and rearwardly from the nozzle 4 is an integral portion 13 40 of the spray head, having therein the conduit 14. This conduit 14 is extended beyond the spray head as at 14', passing through the cap or head 2 of the hand grip 1, where it communicates with the supply 45 conduit 15, leading from any suitable source of supply. At the entrance of the conduit 14 into the passage 12 there has been shown an adjustable closure or regulating screw 17, by which the capacity of the conduit 14 50 may be varied. By the adjustment of the screw 17, the port from the conduit 14 into the passage 12 may be opened and closed to greater or less degree. By this means the spray head is accommodated to fluid of 55 greater or less density or those of more or less viscous nature. As is well known with a given pressure or expenditure of power a greater degree of suction can be exerted through a small orifice than through a 60 large one. Thus with the air pressure as hereafter described, the degree of vacuum exerted through the supply conduit 14 may be varied by the adjustment of the screw 17 to enable the feeding of liquid of different 65 character.

The rearward orifice of the jet nozzle bore forms a valve seat for a reciprocatory needle valve 18, the point of which projects within the bore of the jet nozzle and by its forward movement reduces the inlet orifice of such 70 jet nozzle and in its final adjustment entirely closes the same. The jet nozzle is opened by the retraction of the needle valve rearwardly. The rear end of the jet nozzle is counter-bored to form within the tapered 75 head an enlarged rearwardly open chamber having therein a tapered seat or shoulder 19, leading to the valve seat in the end of the jet nozzle bore, and serving to guide the pointed extremity of the needle valve 80 18. The reciprocatory needle valve 18 is mounted in a head 20, located in the rear end of the barrel 4 and having therein a packing gland 21. The head 20 serves to support and guide the reciprocatory needle 85 valve 18 in its to and fro movement toward and from its seat in the end of the jet nozzle 4. Adjacent to its forward end the reciprocatory needle valve 18 carries an integral collar or peripheral shoulder 22, 90 against which bears one end of a helical actuating spring 23, surrounding the stem of the needle valve, and abutting at its rearward end upon the barrel head 21. This spring 23 normally tends to actuate the 95 valve stem forwardly, causing its pointed forward end to enter within and seat itself in the rear end of the jet nozzle bore. There is thus formed intermediate the rear end of the jet nozzle and the head 21, a receiving 100 chamber 24 for actuating fluid under pressure, with which communicates the fluid pressure conduit 25. This conduit 25 extends through the integral portion 13 of the spray head and is extended as at 25' thence 105 through the closure head or cap 2 of the hand grip or support, where it communicates with a suitable supply hose leading from any source of supply, such as a compressor, pump, reservoir or other analogous 110 means. The air or other fluid under pressure supplied through the conduit 25 enters the concentric air chamber 24, surrounding the valve plunger and passes thence through the jet nozzle if the needle valve 18 is in 115 retracted position. This fluid under pressure rushes through the bore of the jet nozzle, discharging from the pointed end thereof through the discharge outlet 8 of the main discharge nozzle. This rush of air or 120 other fluid induces a suction or vacuum within the concentric receiving chamber 12, which is communicated through the supply conduit 14, drawing therethrough a supply 125 of liquid, which is entrained with the air or other fluid under pressure, and discharged through the main discharge nozzle. The needle valve 18, extends rearwardly beyond the extremity of the barrel 4 and carries a peripherally grooved 130.

collar 30, with which engages the bifurcated head of a short operating lever, 31, pivoted at 32 to the sprayer head. This pivoted operating lever forms one member 5 of a compound control member, the other member of which comprises a trigger arm 34, pivoted at 35, with its upwardly extending bifurcated end, engaging the down-turned arms of the operating levers 31. The 10 retracting or actuating spring 23 surrounding the valve stem tends to draw the needle valve forwardly into contact with its seat in the rearward end of the jet nozzle, and to normally arrest the flow of air under pressure. By the retraction of the trigger arm 15 34, the needle valve is retracted rearwardly thereby opening a direct passage for compressed air through the jet nozzle.

Located in the head 2 of the sprayer 20 port or handle 1 is a control valve for the liquid supply conduit 25. This control valve comprises a reciprocatory plunger, the head 36 of which intersects the passage of the supply conduit 14, to close said passage when 25 moved in one direction, under the influence of the spring 37. This head 36 is provided with a stem 38 which projects laterally through a suitable packing gland 39, beyond the head or cap 2 and into the path of movement of the trigger arm or lever 34. The 30 valve stem 38, however, terminates in spaced relation with the trigger arm or lever 34, whereby the trigger arm 34 is capable of an initial movement independent of the stem. 35 This initial movement of the trigger arm before contacting the laterally disposed stem 38, of the liquid cut off valve, serves to oscillate the operating lever 31 to retract the needle valve 18 against the tension of its 40 spring 23, thereby permitting a preliminary discharge of air under pressure to clear the nozzle and induce the vacuum or suction within the liquid receiving chamber 12, before the cut-off valve 36 is opened. A further 45 movement of the trigger arm 34 then depresses the valve stem 38 against the tension of the spring 37, to move the head 36 laterally out of the liquid supply passage 50 25. The head 36 is preferably, though not necessarily, slightly tapered, in order to insure a tight closing fit. Upon the release of the trigger arm 34, the liquid cut off valve 36 will be seated and arrest the flow of liquid to the sprayer head, before the trigger 55 arm completes its movement. That is to say the supply of liquid will be arrested while the air valve or valve 18 for actuating fluid is still held open. As a result of this differential actuation of the respective 60 valves, a final or supplemental discharge of air is effected, which insures the complete exhaustion of the chamber 12 and sprayer head nozzle, discharging any remaining particles of the liquid and leaving the head in 65 a clean condition preparatory to the next

period of use. This differential control of the respective valves also has another advantage in that it enables the operator to discharge a blast of air upon the surface to be operated upon, by partially depressing or re- 70 tracting the trigger arm 34 to clean the surface by blowing away any dust, dirt or loose particles preparatory to applying a liquid paint, stain or other material.

From the above description it will be apparent that there is thus provided a device of the character described possessing the particular features of advantage before enumerated as desirable, but which obviously is susceptible of modification in its form, 75 proportions, detail construction and arrangement of parts without departing from the principle involved or sacrificing any of its advantages.

While in order to comply with the statute 80 the invention has been described in language more or less specific as to structural features, it is to be understood that the invention is not limited to the specific details shown, but that the means and construction herein disclosed comprises the preferred form of several modes of putting the invention into effect and the invention is therefore claimed in any of its forms or modifications within the legitimate and 85 valid scope of the appended claims.

Having thus described my invention, I claim:

1. In a sprayer head, a barrel, a discharge nozzle at the end of said barrel, a jet nozzle located within the barrel in spaced relation with the discharge nozzle, said jet nozzle having an enlarged head forming a medial closure for the barrel dividing it into a liquid receiving chamber in advance 100 of said head and a fluid pressure receiving chamber in the rear of said head, a screw threaded clamp collar engageable within the barrel for clamping the jet nozzle in position, said head being counter bored from the rear, a tapered seat formed within the counterbore, a reciprocatory valve plunger, spring pressed toward said tapered seat controlling the discharge of fluid under pressure, a guide for said valve plunger spaced 105 rearwardly from the jet nozzle head and clamp collar, thereby affording an intermediate unobstructed chamber through which the plunger extends, means for retracting said valve plunger against the tension of its 110 spring, a liquid supply conduit leading to the liquid receiving chamber in advance of the jet nozzle head and a fluid pressure supply conduit leading to the pressure receiving chamber in the rear of said jet nozzle 115 head.

2. In a sprayer head, a barrel, a discharge nozzle at the end of the barrel, a jet nozzle located within the barrel in spaced relation with the discharge nozzle, a tapered head 120

on said jet nozzle, the bore of said barrel being correspondingly tapered to receive said tapered head, a collar threaded within said bore holding said head to a seat within said tapered bore, a head in the rear end of said barrel, and spaced away from said jet nozzle head and collar, a reciprocatory plunger mounted in said rear barrel head, an actuating spring surrounding said plunger and tending to advance the plunger to close 10 the bore of the jet nozzle, and means to retract said plunger.

In testimony whereof, I have hereunto set my hand this 22nd day of February, A. D. 1922.

HARVEY O. NORRIS.
